UNITED STATES PATENT OFFICE

PERCY B. BALL, OF ATTLEBORO, MASSACHUSETTS, ASSIGNOR TO THE WATSON COMPANY, OF ATTLEBORO, MASSACHUSETTS

DESIGN FOR A SPOON OR SIMILAR ARTICLE

Application filed January 24, 1931. Serial No. 38,437. Term of patent 7 years.

To all whom it may concern:

Be it known that I, PERCY B. BALL, a citizen of the United States, residing at Attleboro, in the county of Bristol and State of Massachusetts, have invented a new, original, and ornamental Design for a Spoon or Similar Article, of which the following is a specification, reference being had to the accompanying drawings, forming part thereof.

Figure 1 is a front elevation of a spoon showing my new design.

Figure 2 is an edge view of the same.

Figure 3 is a fragmentary rear elevation of the same.

Figs. 4, 5, and 6 are sections taken on the line A—A, B—B, and C—C, respectively of Fig. 1.

The dominant feature of the invention resides in the handle.

I claim:

The ornamental design for a spoon or similar article, substantially as shown.

In testimony whereof I have signed my name to this specification.

PERCY B. BALL.
